Abraham E. Dobrin
BY
Arthur L. Sles.
ATTY.

UNITED STATES PATENT OFFICE.

ABRAHAM E. DOBRIN, OF SAN FRANCISCO, CALIFORNIA.

SAMPLE CASE.

Application filed October 22, 1923. Serial No. 670,077.

To all whom it may concern:

Be it known that I, ABRAHAM E. DOBRIN, a citizen of the United States, residing in the city and county of San Francisco and State of California, have invented a new and useful Improvement in a Sample Case, of which the following is a specification.

My invention relates to improvements in sample cases for the carrying and display of merchandise by salesmen, and particularly for sample cases for candy and food products of various kinds wherein it is necessary that the product be held firmly in position and fully enclosed to protect the product from dirt, moisture, and the like.

The primary object of my invention is to provide an improved sample case for the carrying and display of samples.

Another object is to provide an improved device which will effectively protect the samples and which will at the same time afford an attractive display.

A further object is to provide an improved device wherein samples of perishable or easily damaged merchandise may be firmly held in position and effectively enclosed without impairing the attractiveness of the product and of the display.

A still further object is to provide an improved case affording ready access to any of a plurality of samples displayed in the case.

A further object is to provide a device of the character described in which samples may be efficiently carried in a compact space affording increased attractiveness when displayed.

A still further object is to provide a device of improved construction which may be manufactured at low cost and which will combine strength and durability with attractiveness and convenience.

I accomplish these and other objects by means of the device disclosed in the drawings forming a part of the present specification wherein like characters of reference are used to designate similar parts throughout said specification and drawings and in which,

Fig. 1 is a perspective view of my improved sample case in a partially opened position.

Fig. 2 is a transverse section of the case in the closed position.

Fig. 3 is an enlarged transverse section of one of the sample compartments, and

Fig. 4 is a similar section showing a modified construction of the cover and securing means.

The convenience with which samples may be packed and carried and the effectiveness with which the samples may be displayed is, as is well known, of paramount importance to salesmen and others carrying samples for display. This is particularly true of food products and products of fragile or easily damaged character as particular care must be taken to avoid deterioration and damage. My present invention is therefore directed to a case which will afford both convenience and effectiveness of display, and also will afford efficient protection to the product. The sample case herein illustrated and described is designed particularly for samples of candy, which product has been selected for purpose of illustration as being one of the most difficult products to protect and effectively display.

Referring to the drawings the numeral 1 is used to designate in general the bottom portion of a case provided with a top portion 2 hingedly connected thereto by suitable hinges as at 3. The top and bottom portions are provided with oppositely beveled edges arranged to move into proximate relation as at 4 when moved to the closed position as shown in Fig. 2 of the drawings. Suitable clasps 6 are mounted upon the edges opposite the hinges 3 for holding the top and bottom portions in closed position, and a handle 7 is preferably provided for carrying the case.

Backing elements 8 are secured within the back of both the top and bottom portions, said elements 8 having apertures 11 formed therein. When the elements are in position the inner ends of the apertures are closed and form recesses in the back of the top and bottom portions 1 and 2.

Transparent covers 12 are mounted over recess 11. The covers are made cup shaped and are inverted over the recesses to form compartments arranged to receive samples 13 of the product to be displayed which in the present case are various kinds of candies. The edges of the covers 12 engage the backing elements around the edges of the recesses, the depth of the covers being sufficient to accommodate the product to be displayed. Securing elements 14 are mounted adjacent the edges of the recesses to detachably en-

2
gage the covers and hold them in place over their respective recesses. The securing elements consist preferably of pins pivotally mounted upon the backing element and having hooked ends 15 adapted to be turned to extend over the edges of the covers whereby the covers will be clamped tightly against the backing elements and held in position regardless of the position in which the case is placed. The top and bottom portions are made of a depth sufficient to afford a slight clearance between the covers 12 when the case is closed.

The top and bottom portions 1 and 2 are both lined with fabric or other suitable material adapted to make an attractive background for the product displayed, the lining being fitted into recesses to line the inner surface thereof. The outer surface of the case may of course be covered or finished in any manner suitable to the requirements of a case of the character in hand.

In operation, the samples to be displayed are secured within the recesses and the covers 12 placed thereover and secured by means of the securing element 14. In the case of samples of candies, a plurality of pieces of each variety of candy are glued or otherwise secured upon the bottom of each recess, different varieties of candy being placed in each of the recesses, and arranged in an artistic manner to make an attractive display. When the covers 12 are now applied, the edges of the covers are held firmly against the lining 18 of the case so as to exclude moisture, dust and all foreign material. A considerable space is present above the level of the backing elements 8 so that samples may extend well above the surface of the portions 1 and 2 and thus be displayed to best advantage. The samples being secured firmly within the compartments formed by the recesses and covers are effectively protected from injury by contact with each other or with external objects, and the exclusion of moisture and dust retards deterioration so that the samples need be replaced only at comparatively long intervals. The covers 12 are each independently removable so that should it be desired to change the samples in one or more of the compartments the particular cover may be removed to give access to the particular sample without disturbing the remaining samples.

The compartments may of course be made of any desired size, and the number varied in accordance with the size of the case and the number of samples it is desired to display. In the form shown in the drawing I have shown a case arranged to display twelve varieties of candy, and I have also made provision for the carrying of sample containers 16 in one end of the case for samples of special varieties, the containers being engaged by recesses formed in the back-

ing elements 8 and held in position by straps 17 or other suitable securing means.

In Fig. 4 I have illustrated a slightly modified form of the sample compartments wherein the recesses are provided with removable linings 18 of glass or other suitable material which may be removed for cleaning if necessary. The cover is slightly modified by forming a flange 19 adapted to give increased bearing surface against the backing elements, and to be engaged by the securing elements 14. In this case the securing elements can be made shorter as the hook portions will engage the flange in place of extending up over the top of the cover. The samples are secured in position within the lining 18 so as to be held in a desired relation and protected from injury, as above explained, the lining being removable to facilitate the changing of samples when necessary. The linings 18 may be made of any design so as to add attractiveness to the display.

While I have shown what I consider to be the preferred embodiment of my invention as applied in its chief field of utility, the device is of course subject to modification in many ways without departing from the spirit of my invention. I therefore desire to avail myself of all modifications which may fall within the scope of the appended claims.

Having thus described my invention what I claim as new and desire to secure by Letters Patent is,

1. A sample case comprising a pair of hingedly connected top and bottom portions each having a plurality of recesses formed in the back thereof; cup shaped transparent covers mounted over each recess, said covers being inverted over the recesses to form compartment therewith adapted to receive samples of substance to be displayed; and means detachably engaging the covers for holding the same in position.

2. A sample case comprising top and bottom portions hingedly connected along one edge thereof and having a plurality of recesses formed in the backs of said top and bottom portions; cup shaped transparent covers mounted over each recess, said covers being inverted to cover the recesses to form compartments therewith adapted to receive samples of substances to be displayed; and securing elements pivotally mounted adjacent the recesses to detachably engage the covers thereof for holding said covers in position and to permit the independently removal thereof.

3. A sample case comprising top and bottom portions hingedly connected along one edge thereof, the backs of said top and bottom portions being held in spaced relation when the portions are moved to closed relation, said backs having a plurality of re-

cesses formed therein; cup shaped transparent covers mounted over each recess, said covers being inverted over the recesses to form compartments therewith adapted to receive samples of substance to be displayed; and pins pivotally mounted adjacent each cover and provided with hooked ends adapt-

ed to detachably engage the covers to hold the same firmly in position and to permit the independently removal of said covers. 10

In witness whereof I hereunto set my signature.

ABRAHAM E. DOBRIN.
